E. E. HALL

SKI

Filed July 31, 1923

UNITED STATES PATENT OFFICE.

EMIL EDWARD HALL, OF AUBURN, NEW YORK.

SKI.

Application filed July 31, 1923. Serial No. 654,922.

This invention relates to skis and has for its object a particularly simple and efficient construction whereby the packing of snow is prevented beneath the foot and the upper surface of the runner and, also, a particularly simple and efficient means by which the runner is securely fastened to the foot of the user and can be quickly detached and by which the foot, although securely attached to the runner, is capable of having free movement thereto necessary to comfortably and naturally guide the ski.

The invention consists in the novel features and in the combinations and constructions hereinafter set forth and claimed.

In describing this invention, reference is had to the accompanying drawings in which like characters designate corresponding parts in all the views.

Figure 1 is a side elevation of this ski, the foot of the user being shown in dotted lines.

Figure 2 is a plan view of the parts seen in Figure 1.

Figure 3 is a sectional view on line 3—3, Figure 1.

This ski comprises generally the usual runner 1, a foot plate 2 pivoted on its front end on a horizontal axis to the runner and means for securing the foot to the foot plate, the foot plate extending rearwardly under the entire foot and having means for spacing the major part thereof apart from the upper face of the runner to provide a clearance for the snow and prevent the packing of snow.

The runner 1 may be of any suitable form, size and construction. The plate 2 is pivoted at 3 to the runner 1 and, as shown, the plate is formed with downwardly extending lugs 4 or flanges 4, which are pivoted by a horizontal transverse hinge or pivot pin 5 to upwardly extending lugs 6 rising from a base plate 7 secured to the runner 1 in any suitable manner as by screws 8. The plate is preferably boxlike in form and is formed with lengthwise flanges 9 along its opposite sides and with a transverse flange 10 at its rear end, and the means for spacing the ma-

jor part of the plate 2, that is the bottom of the boxlike form from the upper face 50 of the ski is a shoulder 11 located at the rear end of the plate 1 and secured to the flange 10, this shoulder 11 having a comparatively narrow edge, so that it will cut through any snow that might accumulate on 55 the upper face of the ski.

To further prevent the accumulation of snow beneath the plate 2, the runner is formed with lengthwise faces 12, which incline downwardly and laterally from an 60 apex 13 located in the median line of the runner, these surfaces 12 being located between the flanges 9. The lugs 4 at the end of the plate 2 are practically extensions of flanges 9. The front end of the plate 2 preferably curves upwardly at 14 terminating in a fulcrum edge 15 slightly in advance of and above the pivot 3.

The means for securing the foot plate to the foot of the user comprises a toe strap 70 and a harness comprising a heel and an instep strap. 16 designates the toe strap, the opposite ends of which are secured at 17 to the side flanges 9 of the foot plate; this toe strap being formed in two sections which 75 are connected together by a suitable buckle 18 and being practically a pocket into which the toe of the shoe is slipped.

The heel strap 19 is secured to the flanges 9 of the foot plate and extend upwardly 80 and rearwardly in an inclined direction over the heel of the foot. Thus there is a space between the rear edge of the heel strap and the foot plate. The opposite ends of the side portions of this heel strap are pivoted at 85 20 to the flanges 9, these flanges 9 being provided with a plurality of openings 21 which receive the pivots 20 and permit the adjustment of the heel strap forwardly and rearwardly to the foot of the user. The opposite 90 side portions of the heel strap 19 are secured together at their upper ends in any suitable manner as by straps 22, 23 connected by a buckle 24.

25 is the instep strap comprising side sections 26, 27 pivoted at their rear ends at

28, 29 to the side portions of the heel strap 19 between the ends of such portions, the instep strap extending from the heel strap at a right angle or nearly a right angle. The sections 26, 27 are connected together by a clamping member or lever 30 here shown as pivoted at 31 to lugs 32 provided at the front end of one side portion 27, the other side portion 26 of the instep strap being pivoted at 33 to the lever 30 near the outer end of the lever. After the foot has been placed on the foot plate 2 and into the toe strap and heel strap, upon the movement of the lever 30 into a position in which it folds along the side portion 27, the side portion 26 will be tightened across the instep of the user.

The lever is held in its folded position by quick detachable means and, as here shown, 20 a buckle similar to an arctic buckle is used, this comprising a hook-shaped lever 34 pivoted at 35 and coacting with a spring 36 which tends to hold it in either its open or closed position. When the clamping lever 25 30 is folded to its closed position, the lever 34 extends around the bar 36 and, upon moving the lever 34 from its position shown in Figure 2 rearwardly, the lever 30 is locked in its folded position. The lever 34 can be 30 quickly moved to its open position shown in Figure 2 and the lever 30 moved to its open position to permit a quick detachment of the foot from the ski.

The side portion 26 of the instep strap, 35 as here illustrated, is folded upon itself around the pivot 31 and is provided with a plurality of eyes 38 into any one of which a hook 39, provided at the end of the folded part 40 may take, for the purpose of shortening or lengthening the side portion 26 of the instep strap and adjusting it to the foot of the user.

In operation, the heel strap is adjusted so 40 that the joint of the large toe of the operator is directly above the pivot 3 of the foot plate and so that the toe of the shoe extends beyond the front edge or fulcrum 15 of the foot plate and overhangs the runner in such a position that the toes of the shoe engages 45 the runner when the foot plate is inclined a predetermined amount. By reason of the adjustment of the heel strap, the foot can be accurately placed on the foot plate so that the joint of the large toe and also point of 50 the shoe bears proper relation to the hinge 3 and the upper face of the runner.

Also, by reason of the arrangement of the heel strap and the instep strap, the foot is 55 practically held against up and down movement relatively to the foot plate 2 but is capable of slight lateral and endwise movements necessary to control or to comfortably guide the runner, and the heel and instep straps can move on their pivots during 60 the movement of the ankle of the user. In

short, the operating of the runner is flexible and free of any binding or clamping action.

What I claim is:

1. In a ski the combination of a runner, and a foot plate pivoted on a horizontal axis 70 at its front end to the runner, and having a downwardly extending shoulder at its rear end for engaging the upper face of the runner to space the plate from the runner to form a clearance for snow, the shoulder terminating in a comparatively narrow edge to 75 cut through snow on the runner and prevent packing of snow on the runner, substantially as and for the purpose specified.

2. In a ski the combination of a runner, 80 and a foot plate, pivoted at its front end on a horizontal axis to the runner, and having downwardly extending flanges at its sides and rear end, whereby the foot plate is box-shaped in general form, and a clearance for 85 snow is provided between the top of the box-like plate and the upper face of the runner, substantially as and for the purpose set forth.

3. In a ski the combination of a runner, 90 a foot plate pivoted at its front end on a horizontal axis to the runner, and having lengthwise downwardly extending flanges at opposite edges thereof, the runner being provided with lengthwise faces inclined downwardly and laterally from substantially the median thereof, and located between such flanges, substantially as and for the purpose set forth.

4. In a ski the combination of a runner, 100 a foot plate pivoted at its front end on a horizontal axis to the runner, and having lengthwise downwardly extending flanges at opposite edges thereof, the runner being provided with lengthwise faces inclined downwardly and laterally from substantially the median thereof, and located between such flanges, the foot plate also having means at 105 its rear end for resting on the upper face of the ski in the rear of said inclined faces, substantially as and for the purpose described.

5. In a ski the combination of a runner, and a foot plate pivoted at its front end on a transverse horizontal axis to the runner, 110 the plate having an upwardly curved portion above its pivot, terminating in a fulcrum for the foot, above and in advance of the axis of the plate, substantially as and for the purpose described.

6. In a ski and the like, a harness comprising an instep strap, having opposite side portions, and a clamp connecting the side portions comprising a lever pivoted at one end to one side portion, the other side portion being pivoted to the lever, the lever being foldable on to the first side portion, and means for holding the lever in its folded position, substantially as and for the purpose specified.

7. In a ski and the like, a harness comprising an instep strap, having opposite side portions, and a clamp connecting the side portions comprising a lever pivoted at one end to one side portion, the other side portion being pivoted to the lever, the lever being foldable on to the first side portion, and quick releasing means for holding the lever

in its folded position, substantially as and for the purpose set forth. 10

In testimony whereof, I have hereunto signed my name at Syracuse, in the county of Onondaga and State of New York, this 24th day of July 1923.

EMIL EDWARD HALL.
